UNITED STATES PATENT OFFICE.

WILHELM HAGSPIEL, OF LUDWIGSBURG, GERMANY.

STARTING DEVICE FOR EXPLOSION-MOTORS.

No. 802,284.

Specification of Letters Patent.

Patented Oct. 17, 1905.

Application filed July 24, 1903. Serial No. 166,909.

To all whom it may concern:

Be it known that I, WILHELM HAGSPIEL, manufacturer, a citizen of the Empire of Germany, and a resident of 10-12 Imbröderstrasse, 5 Ludwigsburg, Germany, have made certain new and useful Improvements in Starting Devices for Explosion-Motors, of which the following is a specification.

This invention relates to starting mechanism for explosion-motors and operated by hand or through the medium of auxiliary devices which directly the main motor commences to work is thrown out of action automatically. The automatic disengagement is effected not only when the driving-shaft has acquired a greater velocity than that of the starting mechanism, but also when by premature or imperfect firing the shaft of the motor is driven in the reverse direction.

20 The arrangement consists, essentially, in the introduction of a device or means interposed between its coupling and the driving-shaft, which automatically effects the disengagement at the moment of back travel of this latter in case of premature firing.

25 As compared with analogous devices the principal advantages consist in the absence of any fixed connections with the frame of the motor and of springs subject to wear.

30 The invention is illustrated in the accompanying drawings, which show two arrangements, and wherein—

35 Figures 1 to 4 and Fig. 6 show a starting device or mechanism adapted to be operated by hand, and Fig. 5 shows a modification in which an auxiliary device is used. Fig. 1 represents a part sectional elevation of the starting mechanism arranged to be worked by hand. Fig. 2 is a front elevation of the crank. 40 Fig. 3 is a section taken on the line $\alpha-\alpha$ of Fig. 1. Fig. 4 is a detailed view in elevation of the clutch-sleeve of the auxiliary crank. Fig. 5 shows in section the starting mechanism adapted to be actuated by auxiliary means. 45 Fig. 6 represents a side elevation of the starting mechanism arranged to be worked by hand, showing the position assumed by the parts when the engine is fired prematurely and the crank is disengaged from the power-shaft as a result of such premature firing.

50 Referring to Figs. 1 to 4, the arrangement consists of a crank k , provided with clutch-pieces n , which at the moment of starting bear against a carrier-pin h , rigidly connected to the power-shaft f , and turn this latter. The carrier-pin may, however, be replaced by

a sleeve-clutch. The sleeve i of the main crank k is mounted free to turn upon a sleeve d of an auxiliary or secondary crank a , fitting loosely on an extension f of the driving or power shaft. The handle l of the main crank k is of segmental shape in cross-section and partially surrounds the rod or the sleeve b of the auxiliary crank a . The clutch-pieces n of the sleeve i are screw-shaped and adapted to enter 60 spirally-shaped openings or slots o in the sleeve d of the auxiliary crank a and bear against the carrier-pin h on the power-shaft. The relative movement of the two crank-handles is limited by a tenon or stud p , fixed to 65 the sleeve of one of the cranks and guided in a spiral slot q in the sleeve of the other crank.

70 The operation of the hand-operated mechanism just described is as follows: The auxiliary crank a , to which is secured the main 75 crank k by means of the pin p , extending through the slot q of the sleeve i into the sleeve d , is placed upon the power-shaft f , and the segmental handle l of the main crank k is turned until it overlaps the rod b of the 80 auxiliary crank a . On account of the pin p working in the spiral slot q the sleeve i of the main crank will be caused to slide along the sleeve d of the auxiliary crank, and the crank k will approach the crank a . The clutch-pieces n of the sleeve i will then enter through 85 the spirally-shaped openings or slots o in the sleeve d and will abut against the carrier-pin or sleeve-clutch carried by the power-shaft f . The two cranks are then turned together, one 90 hand being kept on the handle l and the other hand on the handle c , and motion will thereby be imparted to the power-shaft f . If there be premature firing, the power or driving shaft revolves in the opposite direction to 95 that of the crank-handle, and the attendant by keeping his hand on the secondary crank-handle c maintains this latter in its movement; but the main crank-handle l , which is driven backward by the pin h on the power or driving shaft, will turn in the opposite direction. There is thus produced a relative movement 100 of the two crank-handles, and the segmental handle l , overlapping the sleeve or the rod b , moves away therefrom. This movement of the two crank-handles produces opposite movements of their sleeves i and d , and by reason of the screw form of the clutch-pieces n and of the openings or slots o , which serve them as guides, as well as by reason of the 105 pin p , moving in the spiral slot q , the clutch-pieces of the sleeve i are caused to move into

the slots *o* and out of engagement with the pin *h*, so that there results a disengagement between the starting-crank and the driving or power shaft.

- 5 When the speed of the motor is greater than that of the crank-handle, no relative and reverse movement of this latter and of the auxiliary crank is produced; but the carrier-pin *h* or the sleeve-clutch of the power-shaft will 10 ride upon the inclined surfaces of the clutch-pieces *n* of the sleeve *i* and move the cranks *a* and *b* longitudinally along the shaft *f* away from the carrier-pin *h*.

In the modification shown in Fig. 5, in 15 which the motor is started by means of an auxiliary motor, both the aforementioned hand-operated cranks of the starting device are replaced by chain-wheels. As an auxiliary motor a hydraulic motor is, by preference, 20 employed, the power for which can, for example, be supplied through pipes. On the shaft *y* of the auxiliary motor are two chain-wheels, one of which, *v*, is fast and the other, *x*, loose. They are connected together by a 25 coupling-pin *z*. There are two of said pins *z* shown, they being pressed outward by coiled springs, the power of which is such that said pins will be automatically disengaged from the wheel *v* as soon as the auxiliary motor 30 has acquired about half of its effective power. The coupling by means of the pin *z* (shown in the drawings) being well known, no description is required. On the power or driving shaft *g* are two loose toothed wheels *r* and *s*, 35 the former of which is provided with screw-shaped slots into which clutch-pieces *n* of like shape engage and which are in one with the toothed wheel *s* behind the wheel *r*. These clutch-pieces press against the pin *h*, which, 40 as in the former arrangement, may be replaced by a coupling-sleeve. The toothed wheels *r* and *s* are connected to the wheels *v* and *x* by chains. The action of this arrangement is as follows: On starting the auxiliary 45 motor the toothed wheel *v* engages and drives the toothed wheel *x* of the power-shaft *y*. The latter transmits movement to the wheel *s*, whose clutch-pieces *n* are in engagement with the pin *h*. Directly the motor is started the disengagement takes place in the well-known manner. The shaft *g*, which has acquired a higher velocity, throws the clutch-pieces *n* back into the spiral slots of the toothed wheel *r*, so that the toothed wheel *s* 55 is displaced laterally on the shaft *g*. If, owing to premature firing, the power-shaft *g* revolves backward, the wheel *s* turns in a reverse direction to that of the shaft *y* of the auxiliary motor. The wheel *s* being connected 60 by a chain to the wheel *x*, and this latter being mounted loose on the shaft *y*, the former is likewise driven in a reverse direction, and hence the disengagement of the toothed wheels *x* and *v* is effected. The wheel 65 *v* being mounted fast on the power or driving

shaft and being connected by a chain with the wheel *r*, this latter rotates in the contrary direction to that of the toothed wheel *s*, so that there is at the same time disengagement between the wheels *r* and *s*—that is to say, 70 of the starting mechanism and the motor.

So as not to necessitate the complete removal of the arrangement and to prevent continual friction between the coupling devices the wheel *s* is held on its laterally-displaced 75 position by a pin *t*, taking into a groove *u*, formed in an extension of the power-shaft, so that the starting mechanism cannot regain its initial position so long as the motor is at work. 80

Having now particularly described and ascertained the nature of my said invention and in what manner the same is to be performed, I declare that what I claim is—

1. A starting mechanism for motors, comprising a shaft having projections, a pair of relatively rotatable elements loosely mounted on the shaft, one of said elements having helical clutch-pieces and the other having slots to permit of said clutch-pieces engaging the projections on the shaft, said slotted member adapted to cause said clutch-pieces to disengage from the shaft when the shaft rotates in an opposite direction. 85

2. A starting mechanism for motors, comprising a shaft, a clutch carried thereby, an auxiliary crank mounted upon the shaft and provided with a sleeve and slots, a crank mounted upon said sleeve and provided with clutch-pieces, said clutch-pieces adapted to extend 90 through the slots in the auxiliary crank and engage the clutch on the shaft, said clutch-pieces further adapted to automatically move out of engagement with the clutch carried by the shaft when said shaft assumes a greater 95 velocity than the crank and thereby disconnect said cranks from the shaft. 100

3. A starting mechanism for motors, comprising a shaft, a clutch carried thereby, an auxiliary crank provided with slots and a 105 sleeve, said sleeve adapted to be loosely mounted on the shaft, a main crank mounted on said sleeve and provided with clutch-pieces, said clutch-pieces adapted to extend through the slots in the auxiliary crank and engage the 110 clutch on the shaft, said main crank further provided with a cam-slot, and a pin secured to said sleeve and adapted to move in said cam-slot for disengaging said clutch-pieces from the clutch on the shaft when the shaft 115 is rotated in an opposite direction owing to back firing, said clutch-pieces further adapted to automatically disengage with said shaft 120 when the latter assumes a greater velocity than said clutch-pieces. 125

4. In a starting mechanism for motors, the combination with a shaft, of an auxiliary crank mounted thereon, a main crank carried by said auxiliary crank and provided with means extending through said auxiliary crank 130

- for connecting the two cranks together, said means further adapted to connect with the shaft, thereby connecting the two cranks thereto to permit of normally rotating the 5 shaft for starting the engine, said means further adapted to automatically disconnect the cranks from the shaft when the latter is caused to rotate in an opposite direction, or when it assumes a greater velocity than said cranks.
- 10 5. A starting mechanism for motors, comprising a shaft provided with a clutch-piece, an auxiliary crank mounted thereon and provided with slots having the end walls thereof beveled, a main crank provided with clutch- 15 pieces adapted to traverse said slots and engage with the clutch-piece of the shaft for imparting movement to said shaft when said cranks are rotated, said clutch-pieces of the main crank further adapted when the shaft 20 rotates in an opposite direction to move against the beveled end walls of said slots and thereby be disengaged from the clutch on said shaft.
6. In a starting mechanism for motors, a shaft provided with a projection, and a plurality of axially-movable members loosely carried by the shaft, one of them having spiral 25 projections and the other having spiral slots to receive said spiral projections for permitting the latter to engage with the projections 30 on the shaft and turn the shaft in a direction to start the motor.
7. A starting mechanism for motors, comprising a shaft, a clutch carried thereby, an auxiliary crank mounted upon the shaft and 35 provided with slots having the end walls thereof beveled, a main crank provided with
- clutch-pieces adapted to traverse said slots and engage with the clutch-pieces on the shaft for imparting movement to said shaft when said cranks are rotated, said clutch-pieces 40 on the main crank further adapted when the shaft rotates in an opposite direction to move against the beveled end walls of said slots and thereby be disengaged from the clutch on the shaft, one of said handles being 45 substantially segment-shaped in cross-section and adapted to partially overlap the other of said handles, whereby said handles may be moved independently or together.
8. A starting mechanism for motors, comprising a shaft having a projection, an auxiliary crank loosely mounted on the shaft and provided with a slot, a main crank mounted on said shaft and provided with clutch means adapted to extend through said slot and engage the projection on the shaft for starting 50 the engine, and a connection between said auxiliary and main cranks, said connection adapted when said main crank is turned in one direction with relation to the auxiliary 55 crank to cause said clutch means to traverse said slot and engage the projection on the shaft and to cause said main crank to move out of engagement with the shaft when said shaft is rotated in an opposite direction owing to 60 premature firing.
- In witness whereof I have hereunto set my hand in presence of two witnesses.
